UNITED STATES PATENT OFFICE.

HENRY TERSTEGGE AND FRANK HENRY GOHMANN, OF NEW ALBANY,
INDIANA, WILTON A. STRATTON, OF LOUISVILLE, KENTUCKY, AND
ROMANUS HENRY GOHMANN, OF NEW ALBANY, INDIANA.

DESIGN FOR A STOVE.

SPECIFICATION forming part of Design No. 17,257, dated April 12, 1887.

Application filed August 27, 1886. Serial No. 212,023. Term of patent 7 years.

To all whom it may concern.

Be it known that we, HENRY TERSTEGGE,
FRANK HENRY GOHMANN, and ROMANUS
HENRY GOHMANN, residing at New Albany,
5 Floyd county, and State of Indiana, and WIL-
TON A. STRATTON, residing at Louisville, Jef-
ferson county, State of Kentucky, citizens of
the United States, have invented and produced
a new and original Design for Stoves; and we
10 do declare the following to be a full, clear, and
exact description of the same, reference being
had to the accompanying photographs, forming
a part thereof.

Our newly-invented design for a stove is
15 clearly represented in the accompanying photo-
graphs, in which Figure 1 represents a stove
in perspective shaped and ornamented in con-
formity with our design; and Fig. 2 represents
20 a plan view of the oval base-plate provided
with an approximately polygonal extension.

Our design consists in the form of base-
plate, body, and top, and the ornamentation
thereof, and in the design for the door. The
base and top are provided with downwardly-
25 inclined edges, which are ornamented by a con-
tinuous series of angular points or arrow-
heads in relief extending around the same.
Below the base of the angular points these
downwardly-inclined edges are provided with
30 a ledge or bead, C, as shown, having points
or projections in relief extending toward the
arrow-heads. Around the edge of the door-
frame of the stove is the raised bead D and the
angular points in relief adjacent to the
35 bead. Within the inclined edges of the door
is the frame E, in relief, of less size than the
main body of the door, leaving a broad smooth
band upon the door around said frame, the
portion of the door lying within the frame
40 being ornamented, as shown. The base-plate
broadens at its forward extremity into a plat-
form approximately polygonal, having four
corners, with the sides between said corners
curving slightly outward.

45 What we claim is—

1. In a design for a stove, the design for the
base-plate, which consists of a main oval body,

and at one end of the oval an extension ap-
proximately polygonal, being provided with
corners and having sides curving slightly out-
ward, the said base-plate having downwardly-
inclined edges ornamented with a series of
arrow-heads, the points of which project up-
ward and along the lower edge, a bead having
points in relief extending toward the arrow-
heads, substantially as described.

2. The design for a stove, which consists of
an oval base-plate having at one end an exten-
sion approximately polygonal, being provided
with corners and having sides which curve
slightly outward, provided with downwardly-
inclined edges ornamented with a series of
arrow-heads, the points of which project up-
ward and along the lower edge, a bead having
points in relief extending toward the arrow-
heads, an oval body, and an oval top plate,
substantially as described and shown.

3. In the design for a stove, the design for
a door, consisting of the main body provided
with inclined edges, a frame in relief upon
the same considerably smaller than the main
body of the door, and an ornamentation within
the frame, substantially as described and
shown.

4. The design for a stove, consisting of the
oval base-plate having at one end a polygonal
extension, the oval body, and the oval top
plate, the said top and base plates having
downwardly-inclined edges ornamented with
a series of arrow-heads, the points of which
project upward and along the lower edge, a
bead having points in relief extending toward
the arrow-heads, substantially as described
and shown.

In testimony whereof we affix our signatures
in presence of two witnesses.

HENRY TERSTEGGE.
FRANK HENRY GOHMANN.
WILTON A. STRATTON.
ROMANUS HENRY GOHMANN.
